VACUUM CLEANER

Osmund Holm-Hansen, Stratford, Conn., assignor to General Electric Company, a corporation of New York

Application November 1, 1934, Serial No. 750,991

10 Claims.

(Cl. 15—8)

My invention relates to vacuum cleaners of the type in which the floor covering or other material being cleaned is drawn toward the suction nozzle and subjected to a beating or sweeping action by 5 a rotating agitating element arranged in the suction nozzle.

The object of my invention is to provide an improved agitating element and arrangement for resiliently supporting the agitating element in the 10 suction nozzle of a vacuum cleaner, and for a consideration of what I believe to be novel and my invention, attention is directed to the accompanying description and the claims appended thereto.

15 In the accompanying drawing, Fig. 1 is a front elevation partly in section of a vacuum cleaner embodying my invention; Fig. 2 is a sectional view taken on line 2—2 of Fig. 1; Fig. 3 is a perspective view of the annulus of resilient material 20 which resiliently supports the agitating element in the suction nozzle; and Fig. 4 is a diagrammatic view showing the action of the agitating element on the floor covering.

25 Referring to the drawing, I have shown my invention in connection with a vacuum cleaner having an outer casing 1 which is provided with a suction nozzle 2 and a discharge conduit 3. A bag 4 for receiving dirt is attached to the discharge conduit. A motor-driven fan, housed 30 within the casing, creates a suction at the nozzle 2 which draws dirt from the surface being cleaned through the suction nozzle and discharges the dirt through the discharge conduit 3 into the bag 4. A handle 5 is provided at the 35 rear of the casing for moving the cleaner. One of the wheels which supports the cleaner is shown at 6.

The suction at the suction nozzle 2 raises the 40 floor covering or other material being cleaned against the bottom edges 7 of the suction nozzle. While held in this position, the floor covering is subjected to a beating and sweeping action by rotatable agitating element 8 arranged in the suction nozzle. The body of the agitating element 45 may be made from wood and has two cylindrical sections 9 at either end and an intermediate rounded section 10. The rounded section 10 provides a pulley by means of which the agitating element is rotated by a belt 11 driven from the end of the motor shaft 12. The body of the agitating element fills the greater part of the suction nozzle so that the air speed through the nozzle is increased. Each of the cylindrical sections 9 is cut away at 9a to provide a flattened 50 surface and has a longitudinally extending brush

13 secured thereon by wedging the rigid back of the brush into a slot 13a in the flattened surface. The flattened surface is parallel to the axis of the agitating element and the longitudinal axis of the flattened surface extends along the axis of 5 the agitating element. The brushes 13 project radially from the flattened surface and the longitudinal axes of the brushes extend along and parallel to the axis of the agitating element. The flattened surface permits the length of the 10 bristles of the brushes 13 to be approximately doubled and therefore permits the use of heavier and more durable bristles without making the brushes too stiff. Each of the brushes 13 extends over substantially half the length of the 15 agitating element, and the brushes are arranged diametrically opposite each other so that the brushes do not simultaneously come in contact with the floor covering being cleaned. Each of the brushes 13 is in contact with the floor covering 20 during about 40° of the revolution of the agitating element and since the brushes 13 are 180° apart, the floor covering is subjected to beating twice per revolution with short, snappy strokes. Each of the brushes 13 moves the floor covering 25 under half of the suction nozzle away from the suction nozzle once during each revolution of the agitating element and subjects the floor covering to a combined beating and sweeping action. With reference to the suction nozzle, the floor covering 30 has a wave-like motion with the node at the center of the agitating element and the upper and lower crests on either side of the center of the agitating element. The floor covering is flexed at the node. When the floor covering is 35 subjected to this type of motion, the beating action of the agitating element is more effective and requires less effort than when the floor covering is merely pushed away from the suction nozzle along the entire length of the agitating element 40 and is not subjected to flexing at the center of the agitating element. A diagrammatic view illustrating the motion of the floor covering is 45 shown in Fig. 4. The full line 23 indicates diagrammatically the position the floor covering assumes when the brushes are in the position illustrated. The node is indicated at 24, and the upper and lower crests at 25 and 26. The dotted line 27 indicates the position the floor covering assumes when the agitating element has rotated 50 180° from the position illustrated. I find that the straight brushes which contact the floor simultaneously throughout their entire length and move a large part of the floor covering away from the suction nozzle at one time produce bet- 55

ter cleaning action and cause less wear than helically arranged brushes of the same stiffness. This may be due to the fact that with straight brushes a greater suction is produced at the 5 nozzle when the brushes are out of contact with the floor covering and consequently the initial impact of the brush with the floor covering produces more effective beating. Also, when the straight brushes move the floor covering away 10 from the suction nozzle, there is a greater reduction in suction and consequently less wear due to the dragging of the brush across the floor covering. By spacing the brushes 9 around the periphery of the agitating element, the power required to drive the agitating element is more uniform and at the same time the advantage of the improved beating action of straight agitating members is retained. The agitating element has a shaft 14 projecting from each end of the cylindrical portion 9 which is rotatably carried in an oilless bearing 15 secured within a cup-shaped bearing housing 16. The agitating element is assembled into the bearing housing 16 by inserting the shaft 14 through the bearing 15 and securing 20 a pin 17 to the projecting end of the shaft to prevent removal of the shaft. The bearing 15 is then pressed into place in the bearing housing 16 and frictionally held therein. Oil soaked waste may be placed in the space between the end of 30 the bearing and the bearing housing.

The bearing housing is resiliently supported in the suction nozzle by an annulus or ring 18 of rubber or other resilient material having a central opening 19 therein which is pressed over the 35 bearing housing 16. Friction between the bearing housing 16 and the inner surface of the rubber ring 18 prevents relative rotation between the bearing housing and the rubber ring. The rubber ring is secured to the inner wall of the suction nozzle by fingers 20a of a spring clip 20. Clip 20 is soldered at 21 to a plate 22. The plate 22 is suitably secured to the inner wall of the suction nozzle. The spring clip is inclined from the axis of the suction nozzle so that the brush 40 may be more readily inserted through the suction nozzle. The fingers of the spring clip frictionally engage the outer surface of the rubber ring and removably hold the agitating element in position 45 within the suction nozzle. To assemble the agitating element in position the rubber rings 18 are pressed over the bearing housings 16 at each 50 end of the agitating element and the agitating element is inserted through the open end of the suction nozzle. The rubber rings are forced between the fingers 20a of the spring clip 20. The 55 rubber rings cushion the vibration of the agitating element thereby decreasing the noise and vibration in the handle. The resilient support provided by the rubber rings resiliently supports the agitating element on its axis of rotation and thereby causes less wear on the material being 60 cleaned. This has been thoroughly shown by tests.

In the operation of the cleaner, the suction 65 at the suction nozzle 2 draws the floor covering toward the lower edges 7 of the suction nozzle. The belt 11 rotates the agitating member 8 which is arranged in the suction nozzle. During about 70 140° of the revolution of the agitating element 8, the both of the brushes 13 are out of contact with the floor covering, and the floor covering is drawn against the lower edges of the suction nozzle. While in this position the suction pressure rises to a relatively high value due to the 75 restriction to the flow of air to the suction nozzle

which is caused by the floor covering. The cylindrical portions 9 of the body of the agitating element prevent the floor covering from being drawn within the suction nozzle. During the next succeeding quarter revolution of the agitating element, one of the brushes 13 is brought into contact with the floor covering. At the instant of impact of the brush with the floor covering, the floor covering is in contact with the cylindrical portion 9 of the body of the agitating element adjacent the flattened surface 9a. The initial impact of the brush 13 with the floor covering jars the dirt loose from the floor covering. Since at this instant the suction at the nozzle is at its highest value, the dirt which is loosened by the jarring or beating is quickly drawn through the suction nozzle. Also the initial impact causes more effective jarring or beating of the floor covering. Continued rotation of the agitating element after the instant of impact pushes the 20 floor covering away from the suction nozzle and the dragging of the brush 13 across the surface of the floor covering subjects the floor covering to a brushing action. Since a large portion of the floor covering is simultaneously pushed away 25 from the suction nozzle, as shown in Fig. 4, there is a considerable drop in suction pressure so that the brushing action causes less wear on the floor covering. The brush 13 remains in contact with the floor covering for substantially 40° of the 30 revolution of the agitating element. During the next 140° of the revolution of the agitating element after the first brush 13 is out of contact with the floor covering, the floor covering is drawn against the lower edges of the suction 35 nozzle as during the first 140° of the revolution of the agitating element, and during the final 40° of the revolution of the agitating element the other brush 13 which is diametrically opposite the first brush 13 subjects the floor covering under 40 the other half of the nozzle to a beating and sweeping action.

During the rotation of the agitating element, the rubber rings 18 resiliently cushion the agitating element. This cushioning action does not 45 to any great degree increase the effectiveness of the beating action caused by the initial impact of one of the brushes 13 with the floor covering. The cushioning does, however, decrease the wear 50 on the floor covering during the subsequent brushing action and also permits the agitating element to align itself with the floor covering so that uneven wear is prevented. The cushioning is particularly effective when used with agitating elements having straight agitating members. 55

What I claim as new and desire to secure by Letters Patent in the United States is:

1. In a suction cleaner, a casing having a suction nozzle, a rotatable agitating element arranged in said nozzle, said agitating element comprising a body portion with an agitating member arranged on the surface thereof, means including a motor for rotating said agitating element, and means for resiliently supporting the body of said agitating element and permitting yielding movement of said agitating element during cleaning.

2. In a suction cleaner, a casing having a suction nozzle, a rotatable agitating element arranged in said nozzle and journaled in a bearing, means including a motor for rotating said agitating element, and means for resiliently supporting said bearing on said casing and permitting yielding movement of said agitating element during cleaning.

3. In a suction element, a casing having a suction nozzle, a rotatable agitating element arranged in said nozzle and journaled in a bearing, means including a motor for rotating said agitating element, and means including resilient material arranged around said bearing for resiliently supporting said bearing on said casing and permitting yielding movement of said agitating element during cleaning.
4. In a suction cleaner, a casing having a suction nozzle, a rotatable agitating element arranged in said nozzle and journaled in a bearing, means including a motor for rotating said agitating element, an annulus of resilient material surrounding said bearing for permitting yielding movement of said agitating element during cleaning, and a clip for removably carrying said annulus on said casing.
5. In a suction cleaner, a casing having a suction nozzle, a rotatable agitating element arranged in said nozzle, said agitating element comprising a body portion having an agitating member projecting therefrom, the longitudinal axis of said member extending along the axis of the agitating element, means including a motor for rotating said agitating element, and means for resiliently supporting the body of said agitating element and permitting yielding movement of said agitating element during cleaning.
6. In a suction cleaner, a casing having a suction nozzle, a rotatable agitating element arranged in said nozzle and journaled in a bearing, said agitating element comprising a body portion having an agitating member projecting therefrom, the longitudinal axis of said agitating member extending along the axis of the agitating element, means including a motor for rotating said agitating element, and resilient material arranged around said bearing for resiliently supporting said bearing on said casing and permitting yielding movement of said agitating element during cleaning.
7. In a suction cleaner, a casing having a suction nozzle, a rotatable agitating element arranged in said nozzle, said agitating element comprising a cylindrical body having a flattened surface with its longitudinal axis extending along the axis of the body, an agitating member projecting from said flattened surface and having its longitudinal axis extending along the axis of the cylindrical body, means including a motor for rotating said agitating element, and means for resiliently supporting the body of said agitating element and permitting yielding movement of said agitating element during cleaning.
8. In a suction cleaner, a casing having a suction nozzle, a rotatable agitating element arranged in said nozzle and journaled in a bearing, said agitating element comprising a body having a plurality of agitating members each extending along a separate portion of the length of the body and projecting radially therefrom, the longitudinal axis of said members extending along the axis of the agitating element and said members being spaced on the periphery of the body of the agitating element so that the agitating members do not simultaneously contact the surface being cleaned, means including a motor for rotating said agitating element, and means for resiliently supporting said bearing on said casing and permitting yielding movement of said agitating element during cleaning.
9. In a suction cleaner, a casing having a suction nozzle, a rotatable agitating element arranged in said nozzle, said agitating element comprising a body having a pair of diametrically opposite agitating members projecting therefrom, the longitudinal axis of each agitating member extending along the axis and along a separate part of the length on the agitating element, means including a motor for rotating said agitating element, and means for resiliently supporting the body of said agitating element and permitting yielding movement of said agitating element during cleaning.
10. In a suction cleaner, a casing having a suction nozzle, a rotatable agitating element arranged in said nozzle and journaled in a bearing, said agitating element comprising a cylindrical body having two diametrically opposite flattened portions, the longitudinal axis of each extending parallel to the axis and along a separate portion of the length of the cylindrical body, a pair of brushes projecting from said flattened surfaces and having their longitudinal axes extending parallel to the axis of the agitating element, means including a motor for rotating said agitating element, and resilient material arranged around said bearing for resiliently supporting said bearing on said casing and permitting yielding movement of said agitating element during cleaning.

OSMUND HOLM-HANSEN.
